United States Patent Office

Des. 192,137
Patented Jan. 30, 1962

192,137

SWEATER OR SIMILAR ARTICLE

Robert Nast, 1900 Ave. W., Brooklyn, N.Y.

Filed July 13, 1961, Ser. No. 65,902

Term of patent 3½ years

(Cl. D3—4)

I claim:

The ornamental design for a sweater, or similar article, as shown.
